UNITED STATES PATENT OFFICE.

LOUIS G. HATOSY, JR., OF NEW YORK, N. Y.

GLASS-CLEANER.

1,083,829.

Specification of Letters Patent.

Patented Jan. 6, 1914.

Application filed February 15, 1912. Serial No. 748,549.

To all whom it may concern:

Be it known that I, LOUIS GEORGE HATOSY, Jr., a citizen of the United States, and a resident of the city of New York, borough of the Bronx, in the county and State of New York, have invented a new and Improved Glass-Cleaner, of which the following is a full, clear, and exact description.

The invention relates to glass cleaners, such as shown and described in the Letters Patent of the United States, No. 975,862, granted to me on November 15, 1910.

The object of the present invention is to provide a new and improved glass cleaner, which is very simple and durable in construction and arranged to permit the bar-keeper or other person to conveniently, quickly and thoroughly clean the glasses, and to allow of setting the cleaner into the washing or rinsing tank of a bar or of removing it therefrom whenever it is desired to do so for replacing worn out brushes by new ones or for other purposes.

In order to accomplish the desired result use is made of a heavy base, adapted to be set onto the bottom of the washing tank, and provided with an opening, and a brushing device having a back fitting into the said opening, the back carrying inclined brush stems provided with brush heads.

A practical embodiment of the invention is represented in the accompanying drawings forming a part of this specification, in which similar characters of reference indicate corresponding parts in all the views.

Figure 1 is a perspective view of the glass cleaner in position in the washing and rinsing tank of a bar, parts being shown in section; Fig. 2 is an enlarged sectional side elevation on the line 2—2 of Fig. 3; and Fig. 3 is a cross section of the same on the line 3—3 of Fig. 2.

The bar A is provided with the usual washing and rinsing tank B having a water supply C and an overflow pipe D for maintaining the water in the tank B at the same predetermined level.

The glass cleaner presently to be described in detail is set onto the bottom of the tank B, and for this purpose the glass cleaner is provided with a base E, preferably made of metal so as to be sufficiently heavy to properly hold the glass cleaner in position in the tank and submerged in the water contained therein. The under side of the base E is concave and it is provided with a central

opening E' into which fits the back F of a brushing device G having brush stems H provided with brush heads I.

The side walls of the opening E' in the base E are bevelled, as plainly indicated in Fig. 2, and the brush back F is correspondingly bevelled so that the brush back can only be inserted into the opening E' from the under side of the base E to prevent the brush back F from being pulled out of the base E. The brush back F is provided with a transversely extending dovetail groove F² into which fit the feet H' of the brush stems H, the said feet being secured in place by screws or nails J extending longitudinally in the brush back and passing through the said feet H, as plainly indicated in Figs. 2 and 3. A spacing block H² is also placed into the groove F' between the feet H', as shown in Fig. 3. The brush stems H are inclined upwardly and are arranged parallel one relative to the other, and the brush heads I are preferably made cylindrical with the outer ends rounded off, as plainly indicated in Figs. 2 and 3. The brush heads I are so arranged that the bristles on the adjacent or opposite sides are in contact with each other so that when a glass is pushed over the brush head I the latter cleans it on the inside and on turning the glass the other brush head I cleans it on the outside.

In practice the brush heads I are below the level of the water contained in the tank B and the barkeeper can readily place a glass upside down over either brush head I and then on turning the glass the interior as well as the exterior of the glass are quickly and thoroughly cleaned especially as the brush heads and the glass are both under the water, and hence the water greatly aids in cleaning the glass and carrying off the extraneous matter, such as foam and the like, loosened by the brush heads on turning the glass as above mentioned.

Whenever it is desired to clean the tank B the glass cleaner can be readily lifted out of the tank B for the time being and returned to the tank after the latter is cleaned.

In case the brush heads I become worn out, the user on removing the glass cleaner from the tank B can readily disengage the brush back F from the base E, and on removing the fastening devices J the feet H' can be readily lifted out of the groove F'. The stems H with new brush heads I thereon

can now be engaged with the groove F' and fastened in place by the fastening means J, after which the brush back with the stems H and brush heads I is placed in position on 5 the base E from the under side thereof, after which the glass cleaner is returned to the tank B.

Although the device has been shown and described in connection with the washing 10 and rinsing tank of a bar, it may be used in washing tanks of counters and other fixtures.

The glass cleaner shown and described is very simple and durable in construction and 15 can be cheaply manufactured and readily applied without requiring any changes in the construction of the tank or other parts of the bar.

Having thus described my invention, I 20 claim as new and desire to secure by Letters Patent:

1. A glass cleaner, comprising a base having a central opening, a brush back removably held in the opening of the base, a stem 25 removably secured to the brush back, and a brush head on the said stem.

2. A glass cleaner, comprising a heavy base having a concave under side and a central opening, the opposite walls of which 30 are beveled, a tapering brush back fitting into the said opening, an inclined stem extending from the said back, and a brush head on the said stem.

3. A glass cleaner, comprising a base provided with a beveled opening, the walls of 35 the opening inclining inwardly and upwardly, a brush back in the opening of the base and having beveled sides, said sides inclining inwardly and upwardly, and a brush

carrying stem detachably secured to the 40 back.

4. A glass cleaner, comprising a heavy base having a concave under side and a central opening, the opposite walls of which are beveled, a tapering brush back fitting into 45 the said opening and provided with a dovetail groove, a brush stem having a foot fitting into the said groove, the stem being inclined upwardly, and a brush head on the 50 said stem.

5. A glass cleaner, comprising a base having a central tapering opening, a tapering brush back fitting in the opening of the base and provided with a groove in its upper 55 face, stems each provided with a foot removably secured in the groove of the brush back, the stems being parallel and spaced apart, and a brush head on each of the stems.

6. A glass cleaner, comprising a base having a concave lower face and provided with 60 a beveled opening, the walls of the opening inclining inwardly and upwardly, a brush back in the opening of the base and having beveled sides, said sides inclining inwardly and upwardly, said back being provided 65 with a recess, a brush carrying stem having a portion fitting in the recess of the back, and a pin in the back and engaging the portion of the stem in the recess, the said pin being below the upper face of the base. 70

In testimony whereof I have signed my name to this specification in the presence of two subscribing witnesses.

LOUIS G. HATOSY, JR.
